UNITED STATES PATENT OFFICE.

JOHN WICKS, OF CHICAGO, ILLINOIS, ASSIGNOR TO AUTOMATIC ELECTRIC COMPANY,
OF CHICAGO, ILLINOIS, A CORPORATION OF ILLINOIS.

AUTOMATIC TELEPHONE SYSTEM.

1,385,347.

Specification of Letters Patent. Patented July 19, 1921.

Application filed February 4, 1918. Serial No. 215,249.

To all whom it may concern:

Be it known that I, JOHN WICKS, a citizen of the United States of America, and a resident of Chicago, Cook county, and State 5 of Illinois, have invented certain new and useful Improvements in Automatic Telephone Systems, of which the following is a specification.

My invention relates in general to improved circuits for use in a system of the automatic type, but which is also adapted for use in manual or semi-automatic systems, especially systems of the latter type, and is especially adapted for use in connection with a trunk line between operators in two exchanges, where composite method of operation is employed. By composite methods I mean that method of operation in which a trunk circuit has two separate and distinct circuits superimposed thereon, one over each of the two conductors of the trunk line.

Among the objects of my invention are to provide an improved method of relaying the ringing current between operators in two exchanges over a composite operating circuit, and to provide improved circuits for accomplishing this result.

In a system in which composite circuits are employed it is common practice to use either one or the other of the superimposed circuits to operate an automatic switch at the far end of the toll trunk instead of employing the operator's cord circuit at that 35 end, and to use the other of the superimposed circuits to operate other automatic switches or for telegraph messages as the conditions may require. In such a system it becomes necessary to provide some means 40 for relaying the ringing current from one end to the other of the toll trunk over the talking circuit extended thereby and past the repeating coils which are included in said toll trunk. In my improved method, I 45 accomplish this result by the use of marginal relays and a high voltage battery over one of the superimposed circuits as will be pointed out.

In the drawing, I have shown a toll trunk 50 C between two toll boards A and B. This toll trunk extends from a jack before the toll operator A to a jack before the toll operator B. Superimposed on the toll trunk C are two separate circuits, one extending 55 from the relay 2 in the upper left hand

corner of the drawing through one winding of a composite coil associated with the toll trunk C, over one conductor of said toll trunk through another composite coil at the far end of said toll trunk and through the 60 relay 3 in the upper right hand corner of the drawing. The relays 2 and 3 may be the line relays of automatic selector or connector switches as desired, which switches may be used to extend connections from the conductors of the toll trunk C to any desired point. Another similar circuit is superimposed upon said toll trunk over the other conductor thereof and may be used to either operate automatic switches or for telegraph 70 purposes.

It will be understood that only the essential circuits are shown in the drawing; and that the apparatus used is merely indicated in the customary diagrammatic manner. 75 For a full disclosure of the operation of automatic switches over composite circuits reference is made to my U. S. Patent #1,315,444, granted September 9, 1919.

Assuming that the operator A desires to 80 establish a connection over the toll trunk C to some subscriber in the same exchange with the B operator, the operations which take place will be briefly described. The A operator in this case inserts the plug of 85 her cord circuit, which may be of any approved type, into the jack 4 associated with the toll trunk C. Now in case the A operator desires to have the B operator complete the connection in the B exchange, the 90 A operator will press her usual ringing key to throw generator out over the plug and jack to the toll trunk, the generator current will pass through the tip springs of the plug and jack, springs 5 and 6, condenser 7, 95 impedance coil 8, relay 9, springs 10 and 11, and ring springs of the plug and jack to the other side of the generator. The condenser 7 and impedance 8 forming a low resistance path for generator current, the relay 9 will 100 operate to close a circuit from ground through springs 12 and relay 13 to battery. Relay 13 upon energizing over this circuit, opens the springs 14 and 15 to prevent ringing current from passing into the composite coils, and at the same time connects the high voltage battery Y in the superimposed composite circuit of the relay 16. Current now flows from said battery Y through the 105 springs 17 and 18 of relay 13, winding 19 of 110

composite coils, conductor 20, winding 21 of the composite coil in B exchange, springs 22 and 23, relay 16, relay 3, and key K' in normal position to ground. This flow of current causes the marginal relay 16 to operate, to in turn close a circuit for the ringing relay 24. The relay 24 upon energizing, connects direct generator through the front contact of its springs and out through the 10 normally closed contacts of the jack before the B operator to operate the drop 25. The B operator in response to this signal inserts her answering plug into the jack and completes the call in the usual manner.

15 In a system of this character it is often desirable to permit the A operator to complete a connection with some subscriber in the B exchange independent of the B operator. In this case the A operator inserts the calling 20 plug into the jack 4 in the usual manner and then instead of operating her ringing key to signal the B operator, she switches the key K from its normal position to close the composite operating circuit from the battery 25 X through the calling device CD, front contact of key K, relay 2 and over the previously traced circuit through relays 26, 16, and 3. The A operator now operates the calling device CD to open and close the 30 above traced circuit to operate an automatic switch at the B exchange through the medium of the line relay 3. Although this circuit extends through the relays 26 and 16, these two relays will not operate at this 35 time, as they are each of low resistance compared with relay 3, and are marginally adjusted.

The relay 3 however operates in the usual manner to step a selector or connector switch 40 with which it is associated to select a wanted line in the B exchange. The operation of this automatic switch extends the conductors 20 and 27 of the toll trunk C to the called line over the conductors 28 and 29. It may 45 be here noted that the transmission of impulses over the above traced composite circuit including the coils 19 and 21, has no effect on the toll trunk C at its ends or upon the other composite circuit which is superimposed upon the conductor 27, as the composite coils, of which 19 and 21 are windings, are connected in the manner usual to such coils, and with the associated condensers and impedance bridges 31 and 32 entirely 50 to prevent interference between the circuits named.

Returning now to the established connection between the A operator and a subscriber in the B exchange, as soon as said connection 60 is completed, the A operator presses her ringing key to throw generator through the coil 9 as previously explained. The energization of the coil 9 has the same effect before mentioned, that is, the battery Y is connected in the operating circuit of the relay 65

3, which circuit also contains the relay 16. The battery Y being of about double the voltage of the battery X, causes the relay 16 to operate to again close the circuit of relay 24, which in turn connects ringing current to the drop 25 and also to the conductors 28 and 29 which have been extended to a called subscriber. The called subscriber's bell will now be operated in the usual manner and upon the response of said subscriber, 70 conversation may be carried on between the A operator and said called subscriber. It will be understood that although as shown in the drawing the drop 25 is connected across the line at this time, the circuit of the 80 drop 25 may be opened at the first selector when the switch is operated, so that when the operator at the A exchange rings on the line the drop will not be disturbed. This circuit may be opened or cut off by any 85 means well known in the art.

The bridges 31 and 32 are connected across the toll trunk C in order to balance the same to assure a good conversational circuit. It will be seen that a call may also be extended from the B operator to a subscriber in the A exchange or to the A operator direct in exactly the same manner by means of the calling device CD' and battery X' which control an automatic switch in the A 95 exchange by means of line relay 2. Also the B operator may then relay ringing current to the A operator or to the called man in the A exchange by means of the relay 33, which is operated by ringing current and 100 which controls the relay 34 to connect the battery Y' in series with the relays 2 and 26. Relay 26 responds to current from battery Y' to connect generator current to the called line or operator through the medium of the 105 relay 35.

It will be seen therefore that I have provided a very simple and highly efficient method of relaying ringing current from one exchange to another in a system in which 110 composite coils and circuits are used for setting up automatic connections. Although I have shown my invention in connection with apparatus of a certain type it will be understood that I do not wish to limit myself 115 to the exact type shown, but that my improved method may be applied as well to any system of well known character without departing from the spirit of my invention.

Having fully described and ascertained 120 my invention, what I consider to be new and desire to have protected by Letters Patent will be pointed out in the appended claims.

What I claim as my invention:

1. In a telephone system, a trunk line, 125 automatic switches for extending connections from either end of said trunk line, operating circuits for said switches having a section in common in which is included one conductor of said trunk line, means for 130

transmitting operating and signaling impulses over said circuit, a relay in said common circuit responsive to a signaling impulse but nonresponsive to the operating impulse, and means controlled by said relay in response to a signaling impulse for signaling a called subscriber.

2. In a telephone system, a trunk line, automatic switches for extending connections from either end of said trunk line, an operating circuit for said switches superimposed on one conductor of said trunk line, relays in said circuit, means for sending impulses from different sources over said circuit to operate said relays, and means controlled by one of said relays responsive to impulses from one of said sources for signaling a called subscriber.

3. In a telephone system, a toll trunk comprising a pair of conductors, a composite circuit superimposed on one of said conductors, automatic switches for extending a connection from one end of said toll trunk, means controlled over said composite circuit for operating said automatic switches, a relay in said composite circuit for connecting ringing current to one end of said toll trunk, and means for operating said relay by an impulse of increased current.

4. In a telephone system, a toll trunk comprising a pair of conductors, a composite circuit superimposed on one of said conductors, automatic switches for extending a connection from one end of said toll trunk, means for sending impulses of current of one strength over said composite circuit to operate said automatic switches, and means for sending an impulse of increased strength over said composite circuit to signal a called subscriber.

5. In a telephone system, a toll trunk comprising a pair of conductors, a composite circuit superimposed on one of said conductors, automatic switches for extending a connection from one end of said toll trunk, a relay in said circuit for controlling the operation of said switches, another relay in said circuit for connecting ringing current to the conductors of said toll trunk, said first relay responsive to impulses of one strength to operate said switches, and said second relay responsive to current of a greater strength to connect ringing current to said toll line.

6. In a telephone system, a two conductor trunk line, a composite circuit superimposed on one conductor of said trunk line, an automatic switch at each end of said trunk line for extending connections from each end thereof, a relay in one end of said composite circuit for controlling the operation of one of said switches, another relay in said composite circuit for controlling the operation of the other of said switches, another relay at each end of said composite circuit for

connecting ringing current to each end of said trunk line, and means for operating said other relays by current of greater strength than that required to operate said first mentioned relays.

7. In a telephone system, a two conductor trunk line, a composite circuit superimposed on one conductor of said trunk line, an automatic switch for extending a connection from one end of said trunk line, a relay in said composite circuit for controlling the operation of said switch, a second relay in said composite circuit for applying ringing current to one end of said trunk line, means for sending impulses of current over said composite circuit to operate said first relay to control said automatic switch, a third relay associated with said trunk line, responsive to alternating current, means for applying alternating current to one end of said trunk line to operate said third relay, and means controlled by said third relay for operating said second relay over said composite circuit to thereby signal a called subscriber.

8. In a telephone system, a two conductor trunk line, a composite circuit superimposed on one conductor of said trunk line, an automatic switch for extending a connection from one end of said trunk line, a relay in said composite circuit for controlling the operation of said switch, a second relay in said composite circuit for applying ringing current to one end of said trunk line, means for sending impulses of one strength over said composite circuit to operate said first relay to control said automatic switch, a third relay associated with said trunk line, responsive to alternating current, means for applying alternating current to one end of said trunk line to operate said third relay, and means controlled by said third relay for connecting current of increased strength to said composite circuit for operating said second relay to thereby signal a called subscriber.

9. In a telephone system, a trunk line, a signal at one end of said trunk line, a controlling circuit for said signal superimposed on one conductor of said trunk line, a relay in said circuit, means controlled by alternating current for sending an impulse of direct current over said circuit to operate said relay, and means controlled by said relay for operating said signal.

10. In a telephone system, a trunk line, automatic switches for extending connections from either end of said trunk line, an operating circuit for said switches superimposed on one conductor of said trunk line, a relay in said circuit, means responsive to alternating current for sending an impulse of direct current over said circuit to operate said relay, and means controlled by said relay for signaling a called subscriber.

11. In a telephone system, a trunk line, automatic switches for extending connections from either end of said trunk line, an operating circuit for said switches superimposed on one conductor of said trunk line, a relay in said circuit, means responsive to alternating current for sending an impulse of direct current over said circuit to operate said relay, and means controlled by said relay for applying alternating current to the called line.
12. In a telephone system, a trunk line, automatic switches for extending connections from either end of said trunk line, an operating circuit for said switches superimposed on one conductor of said trunk line, a relay in said circuit, means responsive to signaling current for sending an impulse of direct current over said circuit to operate said relay, and means controlled by said relay for applying signaling current to the called line.
13. A telephone exchange system comprising a telephone line, a station thereon, an impedance device connected to the line, operator-controlled means at the station for impressing alternating signaling current upon the line circuit, a source of direct current, a first switching means responsive to the signaling current to connect the source of direct current to one conductor of the line circuit at one side of the impedance device, and a second switching means associated with the line circuit on the other side of the device responsive to the direct current flowing in the conductor to connect a source of signaling current to the line circuit.
14. A telephone exchange system compris-
- ing a telephone line, a plurality of stations thereon, an impedance device connected thereto between two of the stations, a source of signaling current at each station, operator-controlled switching means at each of the two stations for connecting the source of signaling current to the line circuit, a second source of current at one of the two stations, a first switching means thereat responsive to the connection of signaling current to the line at such station to connect the second source of current thereat to one conductor of the portion of the line between the two stations, and switching means at the other of the two stations responsive to the current flowing in such conductor to connect the source of signaling current thereat to the line circuit.
15. A telephone exchange system comprising a metallic telephone line, a plurality of stations connected thereto, a source of periodically varying current at each station, switching means at each station for connecting the associated source to the line, a source of constant current at each station, a grounded capacitance device connected to one line conductor at an intermediate point between two of the stations, and means responsive to the operation of the switching means at one of the two stations to connect the source of constant current thereat to such line conductor to cause the operation of the switching means at the other of the two stations.

Signed by me at Chicago, Cook county, Illinois.

JOHN WICKS.
